Jack Gantz, Rye, N. Y., assignor to Empire Brushes, Inc.,
Port Chester, N. Y., a corporation of New York

Application June 11, 1954, Serial No. 30,940

Term of patent 14 years

(Cl. D9—2)

FIG. 1

FIG. 2

FIG. 3

FIG. 4

FIG. 5

Fig. 1 is a top plan view of a clothes brush or similar article showing my new design;

Fig. 2 is a side elevational view thereof;

Fig. 3 is a bottom plan view;

Fig. 4 is an enlarged cross-sectional view taken on the line 4—4 of Fig. 3;

Fig. 5 is an enlarged cross sectional view taken on the line 5—5 of Fig. 3.

The characteristic features of my design for the clothes brush disclosed reside in the ornamentation on the back thereof as best shown in Figs. 1 and 2.

I claim:

The ornamental design for a clothes brush or similar article, as shown and described.
